FLUID DISPENSING DEVICE

Edward S. Garvey, Clayton, Mo.

Application June 9, 1933. Serial No. 675,067

11 Claims. (Cl. 15—138)

This invention relates to fluid dispensing devices, and as an illustration of the invention I will hereafter refer to an inscribing instrument in the form of a fountain brush provided with a self-closing valve which controls the delivery of fluid to the brush. This valve moves toward and away from its seat in response to the ordinary movements transmitted to the brush when the device is in service.

10 In the preferred form of the invention, a normally closed check valve is free to tilt on its seat in response to movements of the fluid dispensing device.

One of the objects is to provide a simple, and 15 convenient means for controlling a loose valve of this kind, so as to regulate the delivery of fluid. The valve is free to move in a suitable housing, and its movements are limited by a stop member adjustable toward and away from the valve. The 20 means for transmitting movement to the stop member preferably includes an operating member exposed at the exterior of the device, so that the user can very easily and quickly regulate the flow at the loose valve. The external operating member can be used to retain the valve on 25 its seat, and thereby prevent leakage when the device is not in service, but another important advantage lies in the control of a loose valve by means of an exposed operating member whereby 30 the flow can be most conveniently regulated to accurately obtain the desired results.

Another object is to prevent leakage at the means for transmitting movement from the external operating member to the internal stop member. A further object is to provide a device 35 of this kind wherein the several parts can be easily assembled and taken apart.

With the foregoing and other objects in view, the invention comprises the novel construction, 40 combination and arrangement of parts herein-after more specifically described and illustrated in the accompanying drawing, wherein is shown the preferred embodiment of the invention. However, it is to be understood that the invention 45 comprehends changes, variations and modifications which come within the scope of the claims hereunto appended.

Fig. 1 is a side elevation of a fountain brush embodying the features of this invention.

50 Fig. 2 is a fragmentary section on a larger scale, taken approximately on the line 2—2 in Fig. 1.

Fig. 3 is a section on the line 3—3 in Fig. 2 showing the parts adjusted to retain the valve in 55 its closed position.

Fig. 4 is a section taken approximately on the line 4—4 in Fig. 2.

Fig. 5 is a view similar to Fig. 3, showing the stop member positioned to permit tilting of the check valve.

To illustrate one form of the invention, I have shown a fountain brush comprising a reservoir 1, a brush tip 2 and a valve housing 3 connecting the reservoir to the brush tip. The lower end of the reservoir is screwed onto the top of the 65 valve housing. The brush member is provided with a threaded ring 4 screwed into the bottom of the valve housing.

The ink, or other fluid, is introduced into the reservoir, and it flows through a passageway 5 70 in the valve housing and thence to the brush member.

The means for confining the fluid in the reservoir includes a check valve 6 having a stem 7 suspended from a valve seat 8. The valve is 75 normally free to tilt on its seat, and the stem 7 may be termed a pendulum which swings, or vibrates, in response to movements of the device, so as to open and close the valve when the brush is in service.

In this form of the invention, the operator grasps the reservoir 1 while moving the brush over a stencil, and the movements of the free valve depend partly upon the speed of the device and partly upon the changes in the direction of 85 its movements. These conditions will vary in different kinds of work, and in the use of a brush, there will be no uniformity in the motions of different operators engaged in the same work.

The problem lies in producing a device wherein 90 the flow can be quickly and accurately regulated, to immediately meet all of the conditions as they arise when the device is in service.

The desired regulation can be obtained by limiting the movements of the free valve, and I will 95 now describe details of a device which meets all of these requirements, with the understanding that the invention is defined by the appended claims, and not by this description of details.

To limit the tilting movements of the valve 6, 100 a pair of horizontal disks 9 and 10 is located in a circular guideway above the valve, said disks being integrally united by means of a vertical member 11, and provided with openings 12 for the passage of fluid through the disks. The lower disk 10 lies immediately above and adjacent to the valve 6, and it serves as an abutment to limit the movements of the valve.

To adjust this stop device toward and away from the valve, a cam 13 in the form of an ec- 110

centric embraced by the disks, may be provided with a horizontal operating shaft 14 at one side of the cam, and a short extension 14' at the opposite side, said extension being journaled in the 5 valve housing.

The shaft 14 passes through an opening which extends laterally from the passageway in which the valve is located, and this opening is threaded to receive an inner threaded member 16 which 10 surrounds the shaft and an outer threaded member 17 also surrounding the shaft. The inner threaded member is firmly seated in this opening to prevent leakage at the screw threads, and it has a recess 18 to receive packing around the 15 shaft, while the outer threaded member 17 has a gland 19 extending into said recess 18, as shown in Fig. 4. Both of these threaded members form bearings for the shaft 14, and they are notched as shown by dotted lines in Fig. 2, to receive a 20 screw driver, or the like, whereby they are inserted into and removed from the threaded opening.

This opening is large enough to permit insertion and removal of the eccentric member 13 25 when the threaded members 16 and 17 are removed. These threaded members cooperate with each other to prevent leakage at the shaft and screw threads when the device is in service.

The shaft 14 has an operating member 21 30 exposed at the exterior of the device, and movable to adjust the stop member 10 toward and away from the valve 6. This operating member may be removably secured to the shaft 14, by means of a screw 22, so that a suitable tool can be conveniently used to remove the threaded members 16 and 17.

It will be understood that the external operating member 21 can be very easily and quickly 40 adjusted to regulate the discharge of fluid from the reservoir 1, and that this adjustment can be readily made to obtain the desired flow which will depend partly upon the kind of work to be done, and partly upon the manner in which the individual operator manipulates the device. In 45 any event, the user will merely adjust the external operating member to control the loose valve 6 which will vary the flow in accordance with the varying conditions arising in the use of the brush.

50 When the device is not in service the self-closing check valve 6 will occupy its closed position while the entire device is approximately vertical, and when desired, the external operating member 21 can be adjusted to positively retain the valve on its seat, as shown in Fig. 2 and Fig. 3.

I claim:

1. A fluid dispensing device comprising a reservoir provided with a discharge port, a valve controlling the flow through said port, said valve being adapted to tilt in response to movements of the reservoir to permit the discharge of fluid from the reservoir, and an adjusting means including an operating member outside of said reservoir for 65 controlling the tilting movement of said valve.

2. A fluid dispensing device comprising a reservoir provided with a discharge port, a valve controlling the flow through said port, said valve being adapted to tilt in response to movements of 70 the reservoir to permit the discharge of fluid from the reservoir, and an adjustable device for controlling the tilting motion of said valve, said adjustable device including a valve regulating member and a manually operated member outside of said reservoir whereby said valve regulating

member is movable toward and away from said valve.

3. A fluid dispensing device comprising a reservoir provided with a discharge port, a valve controlling the flow through said port, said valve being adapted to tilt in response to movements of the reservoir to permit the discharge of fluid from the reservoir, and an adjustable device for controlling the tilting motion of said valve, said adjustable device including an operating member having a portion outside of said reservoir and an internal portion provided with a cam to vary the tilting motion of said valve. 80 85

4. A fluid dispensing device comprising a reservoir provided with a discharge port, a valve controlling the flow through said port, said valve being adapted to tilt in response to movements of the reservoir to permit the discharge of fluid from the reservoir, and an adjustable device for controlling the tilting motion of said valve, said adjustable device including a cam actuated stop member adjacent to said valve, and a shaft having a cam adapted to shift said cam actuated member toward and away from said valve, said shaft having an operating member at the exterior of said reservoir. 90 95

5. A fountain brush comprising a reservoir having bottom provided with a valve seat and a discharge port, a brush below said port, a valve suspended from said valve seat and extending through said port, said valve being tiltable in response to movements of said reservoir to provide for the delivery of fluid to said brush, and a regulating device for controlling the tilting movement of said valve, said regulating device including a circular guideway above said valve, a pair of integrally united disks located in said guideway, said disks having openings to provide for the passage of fluid, a rotatable shaft extending between said disks and having an external operating member outside of said reservoir, said operating shaft having a cam located between said disks, so that said disks will move toward and away from said valve in response to the movement of said external operating member, one of said disks being located above and adjacent to said valve so as to limit the tilting movements of the valve. 105 110 115

6. An inscribing instrument provided with an inscribing tip, a reservoir for the inscribing fluid, a valve to regulate the discharge of fluid from said reservoir to said tip, said valve being free to move toward and away from its seat in response to movements of the inscribing instrument, and means for regulating said valve, said regulating means including an external operating member 125 at the exterior of said inscribing instrument, an internal stop member to limit the movements of said valve, and means whereby movement is transmitted from said external operating member to said internal stop member, the last mentioned means including a cam to actuate said stop member. 130 135

7. An inscribing instrument provided with an inscribing tip, a reservoir for the inscribing fluid, a valve to regulate the discharge of fluid from said reservoir to said tip, said valve being free to move toward and away from its seat in response to movements of the inscribing instrument, and means for regulating said valve, said regulating means including an external operating member 140 at the exterior of said inscribing instrument, an internal stop member movable toward and away from the valve to vary the movements of said valve, an oscillatory cam to actuate said stop 145 150

member, and a shaft connecting said cam to said external operating member.

8. A fountain brush provided with a hand-receiving reservoir, a brush tip, a valve housing between said reservoir and brush tip, a check-valve seated in said valve housing to control the delivery of fluid from said reservoir to said brush tip, said check valve being free to tilt on its seat in response to the service movements of the fountain brush, and means for limiting the movements of said free check valve, so as to regulate the delivery of fluid to the brush tip, said means including an internal stop member adjacent to but separated from free check valve, 5 an external operating member exposed at the exterior of said valve housing, and means whereby motion is transmitted from said external operating member to said internal stop member.

9. A fluid dispensing device provided with a reservoir, a valve to regulate the discharge of fluid from said reservoir, said valve being free to move toward and away from its seat in response to movements of the reservoir, and means for regulating said valve, said regulating means including an external operating member at the exterior of the device, an internal stop member located adjacent to said valve to limit the movements thereof, an internal eccentric member for moving said stop member toward and away from said valve, an oscillatory connecting member uniting said external operating member with said internal stop member, the device being provided with a threaded opening extending laterally from the passageway in which said valve is located, said opening being large enough to permit insertion of the eccentric member therethrough, and a stuffing box screwed into said opening, said oscillatory connecting member being extended through said stuffing box, and the stuffing box 40 being removable to permit removal of said eccentric member.

10. A fountain brush provided with a reservoir, a brush tip, a valve housing between said reservoir and brush tip, a valve located in said housing to control the delivery of fluid from the reservoir to the brush tip, said housing being provided with a screw-threaded opening extending laterally from the passageway in which the valve is lo-

cated to the exterior of the housing, a valve-controlling member extending through said threaded opening and provided with an operating member at the exterior of the valve-housing to control the movements of the valve, and a stuffing box in which valve-controlling member is supported, said stuffing box including inner and outer threaded members screwed into said lateral opening, one of said threaded members being provided with a recess to receive packing and the other being provided with a gland extending into said recess.

11. A fountain brush provided with a hand-receiving reservoir, a brush tip, a valve housing connecting said reservoir to said brush tip, a self-closing check valve located in said valve housing to control the delivery of fluid from said reservoir to said brush tip, said valve being free to move toward and away from its seat in response to the service movements of the fountain brush, said housing being provided with a screw-threaded opening extending laterally from the passageway in which the valve is located to the exterior of the housing, regulating means including a stop member in said passageway to limit the movements of said self-closing check valve, a cam to move said stop member toward and away from said valve, said cam being in the form of an eccentric embraced by said stop member, said threaded opening being larger than said cam to permit insertion of the cam into said passageway, an operating shaft secured to said cam and passing through said threaded opening, said shaft having an operating member exposed at the exterior of said valve housing, an inner threaded member surrounding said shaft and seated on the wall of said opening movement to prevent leakage at the threads, an outer threaded member screwed into said threaded opening, and packing between said inner and outer threaded members 115 to prevent leakage at said shaft, one of said threaded members being provided with a recess to receive the packing, the other being provided with a gland extending into said recess, and both of said threaded members being removable from said 120 threaded opening to permit removal of said cam.
